GLAZING BEAD

John Kenneth Rimington, 10562 109th St.,
Edmonton, Alberta, Canada

Filed July 14, 1967, Ser. No. 7,803

Term of patent 14 years

(Cl. D13—6)

FIGURE 1 is a top plan view of a glazing bead showing my new design;

FIGURE 2 is a front elevational view of the glazing bead of FIGURE 1, said front and rear elevational views being identical;

FIGURE 3 is a bottom plan view of the glazing bead shown in FIGURE 1; and

FIGURE 4 is a right end elevational view of the glazing bead shown in FIGURE 2, it being understood that a left end elevational view of the glazing bead shown in FIGURE 1 would be a mirror image of the view shown in FIGURE 4.

I claim:

The ornamental design for a glazing bead, as shown and described.
